UNITED STATES PATENT OFFICE.

RALPH V. SAGE, OF WESTMONT BOROUGH, PENNSYLVANIA, ASSIGNOR TO CAMBRIA STEEL COMPANY, A CORPORATION OF PENNSYLVANIA.

CAR CONSTRUCTION.

1,110,236.

Specification of Letters Patent. Patented Sept. 8, 1914.

Application filed June 20, 1913. Serial No. 774,853.

To all whom it may concern:

Be it known that I, RALPH V. SAGE, a citizen of the United States, residing in the borough of Westmont, in the county of Cambria and State of Pennsylvania, have invented certain new and useful Improvements in Car Construction; and I do hereby declare the following to be a full, clear, and exact description of the invention, such as will enable others skilled in the art to which it appertains to make and use the same.

My present invention comprises certain improvements in metallic railway cars, and more especially to gondola or other cars which have a plurality of drop doors located between the cross bearers of the floor framing and form the floor of the car to a considerable extent when the said doors are closed.

One of the objects of my invention is to so construct the cross bearers or transoms, and body bolsters with their outer ends beveled or inclined downwardly so as to provide a convenient and accessible space and mounting for the door operating shaft which extends longitudinally of the side of the car, near its outer lower edge.

Another object of my invention is the construction and arrangement for mounting the operating shaft on journal bearings which are supported on reinforcing angular bracket strips, which connect the lower end of each side stake with the outer end of the cross bearer, the journal bearing being substantially independent of the cross bearer, so that the shaft will be sustained directly by the plate girder side of the car.

Another object of my invention consists in forming the locking latches for the doors with upwardly extending noses or hooked ends adapted to rest on the operating shaft when the doors are closed and thereby lock or sustain them in that position.

A further object of the present invention is to provide certain other improvements in car construction which will be hereinafter described.

Having thus given a general description of my invention, I will now, in order to make the matter more clear, refer to the accompanying one sheet of drawings forming part of this specification, in which—

Figure 1 is a vertical transverse sectional elevation of a portion of a gondola car illustrating my invention, taken on the line I—I

of Fig. 2 showing the doors of the car in their closed position, the nose or hooked end of a latch seated on the door operating shaft, whereby the doors are locked in that position, a cross bearer of channel section and body bolster of open box shape, both having beveled or downwardly inclined outer ends attached to the lower ends of the car stakes. Fig. 2 is a side elevation of a portion of the car corresponding to that shown in Fig. 1. Fig. 3 is a vertical transverse sectional elevation of the side corner of a car taken on the line III—III of Fig. 2 looking in the direction of the arrows, showing more clearly the manner in which the end of the cross bearer is inclined and attached to the lower end of the car stake and the manner of mounting the journal bearing for the car door operating shaft. Fig. 4 is a vertical transverse sectional elevation taken on the same line and of the same part of the car as that shown in Fig. 3 but showing a pressed metal cross bearer of open box form, instead of a rolled channel shape; and Fig. 5 is a vertical transverse sectional elevation similar to Figs. 3 and 4, but showing the end of a channel or I-beam shape of a cross bearer inclined or bent downwardly.

Referring now to the numbers of reference on the drawings: 1 indicates the center sills of the car which may be of any desired construction, but shown as rolled channels disposed back to back with their webs vertical, the flanges thereof extending horizontally outwardly toward the sides of the car and spaced apart by means of flanges shallow box-shaped members 2 and 3, which are located between the center sills at the points of connection of the inner ends of the cross bearers and bolster members to the center sills.

A cover plate 4 is laid over and riveted to the top flanges of the center sills 1 and to the top flanges of the box-shaped members 2 and 3 and serves as the central floor strip of the car.

5 indicates the bolsters of the car which are shown as open box-shaped members of trapezoidal outline, but which may be of any well known construction.

The cross bearers 6 are spaced at suitable distances apart between the bolsters, having their inner ends attached to the center sills 1 in any approved manner and extending outwardly therefrom to the sides of the car

and secured to the lower end of the car stakes 7. The outer ends of these cross bearers 6 are bent downwardly or beveled on their upper surfaces as at 8. This may 5 be done by cutting away an angular portion as shown in Figs. 1, 2 and 3, by constructing the cross bearer of pressed metal with an upper inclined outer end as illustrated in Fig. 4, or by bending downwardly the entire 10 end of the cross bearer, as shown in Fig. 5, the idea being to provide a space for the door operating shaft, latches, journals, etc., which is readily accessible and whereby the shaft may be mounted or demounted easily 15 when desired.

The outer ends of the cross bearers are riveted directly to the lower ends of the car stakes 7 and are further reinforced and connected together by means of a bent angular bracket member 9, the vertical flange or leg of which is riveted to the lower end of the car stake and the outer end of the cross bearer, its other leg extending outwardly at right angles thereto and having 20 mounted thereon a bearing 10 in which is journaled the longitudinal door operating shaft 11 adapted to operate and support the forward swinging ends of the doors 26, through the door operating mechanism 25 mounted on the under sides thereof. This car door locking mechanism is an improvement on the construction shown in my co-pending application, filed October 3rd, 1912, Serial Number 723,665, and comprises a pair 30 of latch-bars 12 for each door, which are slotted as at 13, within which the tubular rollers 14 are mounted and retained in place between the angular brackets 27 by means of bolts 15 which form the axles for the 35 rollers 14.

The forward end of each latch-bar 12 extends upwardly and is formed into a short projecting nose or hook 16 and normally rests, and is held, on the door operating 45 shaft 11 when the door is closed, its upper forward face being beveled as at 17, so that it will pass by the operating shaft when the door is being closed. A chain 18 has one end attached to the underside of the latch-bar 12 by means of an eye-bolt 19 and its opposite end is secured to the door operating shaft 11 by a bolt 20, which chain is wound or unwound on said shaft in closing or opening the door.

50 The car door is hinged at 21 to the center sills of the car, its forward edge being adapted to close against the lower flange of a corner shedding member 22 of trough-shape, which also forms the bottom chord 55 of the plate girder side 23 of the car, while the sides of the door close against the projecting edges of the transverse floor strips or cover plates 24 which are attached to the top flange of each cross bearer and bolster 60 which strips serve as that portion of the

floor of the car between the car doors. The web of the plate girder side may also extend downwardly to the transoms as shown in Fig. 5 and may also have a reinforcing strip or angle 28 on its lower edge.

When it is desired to open the doors of the car to dump the lading, or for any other purpose, a wrench is applied to the squared outer end of the operating shaft (not shown) and the shaft is rotated in the direction of the arrow shown in Fig. 1, and in so doing, the projecting lug 25, which is attached to the operating shaft, comes into contact with the forward projecting nose or hook 16 and pushes the latch backward on its roller bearings beyond the circumference of the operating shaft and unlatches the door, and the continuation of said movement further unwinds the chain from the shaft. The door is thereby allowed 85 to swing downwardly into a substantially vertical or inclined position, as desired. In closing the door the shaft is rotated in the reverse direction, the chain is wound upon the shaft and when the forward upper beveled surface 17 of the nose comes into contact with the operating shaft, it will slide on it and be seated on the shaft in the position shown in Fig. 1 of the drawings.

The construction of the lower portion of the side of the car, including the inwardly inclined corner shedding member 22, which is provided with thickened edge flanges arranged obliquely to the web portion, connected to the lower edge of the web 23 of the plate girder car side, to the cross bearer or transoms and to the body bolsters in connection with the downwardly extending stakes 7 which are secured to the extreme ends of the cross bearers and body bolsters, all form an exceedingly strong and efficient lateral brace to tie the sides and the bottom of the car together, while the member 22 also serves as the bottom flange of the plate girder side; the corner shedding member 22 being arranged to slope downwardly and inwardly at the lower side corner of the car, thus forms a sloping surface which is well adapted to discharge the lading to the door opening and will prevent any entanglement of the same in what would otherwise be the reentrant angle of the car body. Further than this, the corner construction provides a convenient means, space and accessible location in which to arrange the door operating shaft, its bearings, mountings and appurtenances, without detracting from the carrying capacity of the car, while adding to the strength of the structure as previously explained.

It will be understood that the plate girder side of the car is primarily supported by the ends of the bolsters, and through them, transmits the load to the trucks.

While I have shown and described my

invention in considerable detail, I do not wish to be limited to the exact details of construction specified, but may use such substitutions, modifications or equivalents 5 thereof, as are embraced within the scope of my invention, or as pointed out in the claims.

Having thus described my invention, what I claim and desire to secure by Letters Patent is—

- 10 1. In a car of the character described, a plate girder side, a plurality of upright stakes extending downwardly below the lower edge of the web of said side, a plurality of cross transoms and bolsters extending transversely of the car attached to the lower ends of the stakes aforesaid, the upper portions of the outer ends of said transoms being downwardly inclined, a trough-shaped bottom chord member arranged 15 obliquely and secured to the lower portion of the web of the plate girder side and to the cross bearers and transoms aforesaid and extending longitudinally of the said car, whereby the car is braced and a space 20 provided for the door operating shaft and mountings.

2. In a car of the character described, provided with center sills and plate girder sides, a plurality of transoms and bolsters 30 extending transversely of the cars and secured by their inner ends to the center sills, the upper portions of the outer ends of the said transoms and bolsters being downwardly inclined, a plurality of upright 35 stakes secured to the plate girder sides extending downwardly below the lower edge of the web of the same and attached to the outer extremities of the cross transoms and bolsters aforesaid, a trough shaped shedding 40 member secured by one edge to the plate girder side, inclined inwardly and downwardly therefrom, and secured to the transoms and bolsters and forming the bottom chord member for the plate girder side; and 45 a door operating shaft mounting in the opening thereby provided.

3. In a car of the character described, plate girder sides provided with a plurality of stakes attached thereto, with their lower 50 ends depending therefrom, cross bearers and transoms extending transversely of the car, the extremities of the same being attached to the lower ends of the stake, a downwardly and inwardly sloping trough-shaped 55 shedding member extending longitudinally of the car, and secured to the lower part of the plate girder side and to the cross bearers and transoms aforesaid and forming the bottom chord member for the plate 60 girder side, a bracket attached to the lower ends of each of the stakes and to the outer end of each of the cross bearers and transoms, bearings secured to said brackets and a longitudinally extending operating shaft 65 mounted in said bearings.

4. In a car of the character described, provided with center sills and plate girder sides, cross bearers and transoms secured to the said center sills extending transversely of the car, a plurality of stakes attached 70 to and extending below the plate girder sides and secured to the extremities of the cross bearers and transoms aforesaid, an angular bracket connected to the lower end of each of the said stakes and to the corresponding cross bearers and transoms, journal bearings mounted on said brackets, floor strips secured to the tops of the cross bearers and transoms and projecting laterally therefrom, swinging doors hinged to the 80 center sill, a door operating shaft mounted in the bearings aforesaid and provided with operating locking mechanism adapted to close and open the doors.

5. In a car of the character described provided with plate girder sides, a plurality of cross bearers and transoms extending transversely of the floor framing, said plate girder having a bottom chord composed of a trough-shaped member with inclined 85 flanges, one of which is secured to the lower edge of the plate girder, the other flange being secured to the cross bearers and transoms, thereby providing a shedding surface and a space for the door operating shaft 90 and mountings.

6. In a car of the character described, a plate girder side, a plurality of cross bearers and transoms extending transversely of the floor framing, a corresponding plurality 100 of stakes attached to said plate girder side and to the extremities of the cross bearers and transoms, an inclined shedding bottom chord member for the plate girder side of trough-shape having a central web portion 105 with inclined thicker edges, one of which is secured to the plate girder side and the other to said cross bearers and transoms, thereby forming a space for the door operating shaft and mountings.

7. In a car of the character described, a plate girder side, a bottom chord member therefor comprising a trough section having a central web portion with inclined thicker flanged edges, secured by one of 115 the said edges to the plate girder side, the other edge being attached to the floor framing contiguous to the door opening and also forming the shedding plate adapted to discharge the lading through the door openings.

8. In a car of the character described, provided with a plurality of drop doors hinged longitudinally near the center framing thereof, an operating shaft mounted in 125 the space below the outer lateral edges of the car floor, a latch slidably mounted on tubular bearings on the outer edges of each door and provided with an upwardly projecting hooked nose adapted to engage and 130

rest upon the operating shaft above the body of the latch, and connections between said shaft and said latch

9. In a car of the character described, a plurality of drop doors hinged longitudinally of the floor thereof, a plurality of cross bearers and transoms extending transversely of the car, floor strips secured on and extending over the horizontal upper surfaces of the said cross bearers and transoms, said cross bearers and transoms each having a downwardly inclined outer end, a plate girder side provided with a corresponding plurality of side stakes projecting below the lower edge of the same and secured to the outer extremities of the cross bearers and transoms aforesaid, an inclined shedding member attached to the lower portion of the plate girder side and to the cross bearers and transoms aforesaid and forming the bottom chord for the plate girder side, an operating shaft mounted below said shedding member, and means coöperating with said shaft for operating and locking the said doors.

10. In a car of the character described, a plate girder side, a plurality of stakes secured thereto, projecting below the lower edge thereof, a plurality of cross bearers and transoms extending transversely of the car and having the outer ends of their upper surfaces downwardly inclined and their extremities secured to the lower ends of the

stakes aforesaid, an angular bracket secured to and connecting the lower ends of said stakes and the outer ends of said cross bearers and transoms, and shaft bearings mounted on said brackets.

11. In a car of the character described, a plate girder side, a plurality of cross bearers and transoms extending transversely of the floor framing, a plurality of upright stakes secured to and projecting below the said sides, their lower ends being secured to the outer ends of the cross bearers and transoms aforesaid, angular brackets secured to and connecting the lower ends of the said stakes to the outer ends of the cross bearers and transoms, bearings supported upon said brackets, an operating shaft extending longitudinally of the car and mounted in the bearings aforesaid, a plurality of doors hinged to the longitudinal center framing of the car, latches on the outer edges of the said doors adapted to slidably move on tubular bearings on the same, each latch being provided with an upwardly extending hooked end projecting above the body of the latch, and flexible connections between said shaft and said latches.

In testimony whereof I hereto affix my signature in the presence of two witnesses.

RALPH V. SAGE.
